UNITED STATES PATENT OFFICE.

THOMAS J. DUNN, OF NEW YORK, N. Y., ASSIGNOR TO KNIGHTS OF COLUMBUS, A CORPORATION OF CONNECTICUT.

DESIGN FOR A BADGE OR SIMILAR ARTICLE.

SPECIFICATION forming part of Design No. 35,179; dated October 15, 1901.

Application filed September 12, 1901; Serial No. 75,232; Term of patent 3½ years.

To all whom it may concern:

Be it known that I, THOMAS J. DUNN, a citizen of the United States, residing at New York, in the county of New York and State of New York, have invented and produced a new and original Design for a Badge or Similar Article; and I do declare the following to be a full, clear, and exact description of the same, reference being had to the accompanying drawing, forming a part thereof.

This invention relates to a design for a badge or similar article and which may be used as a badge, pin, watch-charm, or like article.

As shown in the drawing, the badge is in the form of an Isabella cross surmounted by a dove flying toward the Western Hemisphere,

which is shown on the lower part of the tree of the cross.

As indicated in the drawing, the body of the cross is red, the dove white, and the hemisphere blue.

Having thus described my invention, what I claim as new, and desire to secure by Letters Patent of the United States, is—

The design for a badge or similar article substantially as herein shown and described.

In testimony whereof I have hereunto set my hand and affixed my seal in the presence of two witnesses.

THOS. J. DUNN. [L. S.]
